UNITED STATES PATENT OFFICE.

HENRY J. ABRAMS, RICHARD T. LIDDICOAT, AND FRANK H. STEVENS, OF ANN ARBOR,
MICHIGAN.

AERIAL TOY.

Application filed May 23, 1925, Serial No. 32,375. Renewed July 28, 1926.

The present invention consists of an aerial toy and has for an object the provision of novel means for projecting an element into the air and simultaneously imparting a rotary movement thereto.

A further object of the invention is to provide a toy of this character which will project the air piece into high altitudes while being rotated, the air piece being so constructed that its descent will be gradual and graceful to present a picturesque figure.

A co-ordinate object of the invention is to provide a toy of this character which is made of durable material and constructed to effect very efficient functioning of the device and is operable in a convenient manner to permit projection of its air piece in any desired plane.

Other objects of the invention will be apparent from the following description of the present preferred form of the invention, wherein:—

Fig. 1 is a longitudinal sectional view of an aerial toy constructed in accordance with the present invention showing the aerial piece removed therefrom and showing a part of the handle in side elevation;

Fig. 2 is a cross-sectional view of the aerial piece;

Fig. 3 is a plan view of the same;

Fig. 4 is a plan view looking at the inner face of the movable part of the impelling member; and

Fig. 5 is a similar view of the outer face of said part.

The device of the present invention consists of an impelling member generally designated 6 and an air piece generally designated 7. The impelling member consists of a body shaped like a revolver having a barrel 8 and a handle 9. The body is preferably constructed from a single sheet of metal and has a portion of the bottom of the barrel struck out to provide a trigger chamber 10. The impelling member includes a movable part generally designated 11 which comprises a circular shell or drum 12 which has arms 13 radiating therefrom at diametrically opposite points. The disk comprising the outer face of the drum is pressed out to provide a concentric stud 14 while the disk comprising the inner face of the drum has an elongated cylindrical tube 15 issuing therefrom which is concentrically mounted in the barrel 8. It will be noted that both faces

of the drum 12 are in a plane appreciably beyond the plane of the faces of the arms 13. The inner face of the drum has fingers 16 struck inwardly thereon thereby providing tapered slots for a purpose hereinafter described. The outer face of the shell is provided with lugs 17 one of which lies near each arm 13 as shown to advantage in Fig. 5.

The impelling member also includes a helical spring 18 the convolutions of which encircle the tube 15, the innermost convolution being anchored on the inner end of the barrel 8, as indicated at 19, while the outermost convolution is anchored on the inner face of the drum 12, as indicated at 20.

An additional part of the impelling element consists of a trigger 20 embodying a rod one end of which is engageable in any one of the slots formed by striking in the finger 16 while the opposite end is formed to provide a finger piece 21 arranged in close proximity to the handle 9 of the body. The rod 20 is equipped with an intermediate annulus 22 which rides in a depression 23 formed in the barrel 10. A coil spring 24 is mounted on the rod 20 one end of which abuts the annulus 22 while the opposite end abuts the inner wall of the depression 23. The spring 24 bears against the annulus 22 to force the outer end of the rod into engagement with the inner face of the drum 12. The rod is so positioned that it will successively engage the tapered slots formed by striking in the fingers 16, the latter yieldingly embracing the rod in an apparent manner.

The air piece in the present instance is of circular configuration and consists of a rim 25 the marginal edge of which is bent at right angles to provide an annular flange 26. A hub 27 is formed concentrically in the rim and has a series of blades 27' radiating therefrom, portions of the outer end of which are formed integral with the rim 25. The unconnected portion of each blade is pressed inwardly and has one of the margins thereof bent at right angles as indicated at 28 and shown in Fig. 2. It will be noted that the pressed in portions of the blades 27' are housed by the annular flange 26 to prevent direct contact of the blades with an object during the flight or trajectory of the air piece. The hub 27 is provided with a central opening 29 which corresponds to and is adapted to receive the stud 14. The hub is also provided with slots 30 which conform to

the configuration of the lugs 17 and are adapted to receive the latter thereby providing a connection between the aerial member and the impelling member.

5 In use of this device the movable part of the impelling member is turned in a clockwise direction until the helical spring 18 has been wound. During this winding movement the outer end of the trigger successively engages the different slots formed by the striking in of the fingers 16. The trigger prevents reverse rotation of the movable part in an apparent manner. After this, the air piece is mounted upon the movable part 15 of the impelling member in a manner heretofore described and the trigger is then pulled. When the trigger is pulled the movable part of the impelling member is simultaneously thrust outwardly and rotated so 20 as to impart both an impelling and rotating movement to the air piece. In view of the peculiar construction of the blades of the air piece the latter will be elevated to relatively high altitudes and after having reached the 25 peak of its ascent will begin to gravitate gradually and gracefully particularly in view of its especial construction. The impelling member is of such construction that it may be conveniently grasped in the hand 30 and conveniently operated for starting the air piece on its flight in the manner above described.

We are aware that numerous changes may be made in this device in order to produce 35 varied effects of the air piece during flight and after its descent. We have above described, however, only a single form of the invention by the principle involved therein.

What is claimed is:—

40 1. An aerial toy including an impelling element comprising a revolver shaped body

and a tube concentrically mounted in the barrel of the body the outer end of which issues into a drum with radial arms, a spring encircling said tube having one end anchored 45 on said drum and the other end anchored on the revolver barrel, a trigger carried by the barrel and engaged with said drum, and an air piece mounted on said drum.

2. An aerial toy including a revolver 50 shaped body equipped with a movable part embodying a tube mounted in the barrel of said body, a spring encircling said tube one end of which is anchored on said body and the opposite end anchored on said movable 55 part, a trigger directly engaged with said movable part beyond the end of the revolver barrel to hold the latter in a fixed position against the resistance of said spring, and an air piece mounted on said movable part and projected therefrom by said spring when the trigger is released.

3. An aerial toy comprising an impelling member which includes a movable part embodying a circular drum having a portion 60 thereof pressed out to provide a concentric stud, and an air piece mounted on and engaged to said drum and provided with a central opening to receive said stud.

4. A flying toy including a revolver shaped 70 body a portion of the barrel of which is pressed out to provide a trigger chamber, a spring actuated member mounted in said barrel, an air piece engaged with said member, and a spring actuated trigger mounted 75 in said chamber and engaged with said member.

In testimony whereof we affix our signatures.

HENRY J. ABRAMS.
